UNITED STATES PATENT OFFICE.

HOWARD G. TALLERDAY, OF SAN FRANCISCO, CALIFORNIA, ASSIGNOR TO WESTERN PIPE AND STEEL COMPANY OF CALIFORNIA, A CORPORATION OF CALIFORNIA.

ICE CAN.

1,423,278.

Specification of Letters Patent.

Patented July 18, 1922.

Application filed April 28, 1921. Serial No. 465,321.

To all whom it may concern:

Be it known that I, HOWARD G. TALLERDAY, a citizen of the United States, residing at the city and county of San Francisco, 5 State of California, have invented a new and useful Ice Can, of which the following is a specification.

My invention relates to ice cans of the type commonly used in the manufacture of 10 artificial ice. Ice cans of this type are filled with water and placed in brine tanks in which the temperature of the water is lowered to the freezing point thereby producing a cake of ice in each can. The can containing 15 the cake of ice is then removed from the brine, tipped over on its side and the cake of ice removed. It is necessary that cans of this type be made very strong, especially at the bottom, to withstand the heavy weight 20 of the ice and the rough handling to which they are subjected.

One of the objects of my invention is the production of a can of the class described of simple and durable construction.

25 Referring to the drawings which are for illustrative purposes only,

Fig. 1 is a perspective view of an ice can embodying a form of my invention.

Fig. 2 is a sectional view on line 2—2, 30 Fig. 1.

Fig. 3 is a sectional view on line 3—3, Fig. 1.

Fig. 4 is a sectional view on line 4—4, Fig. 1.

35 Fig. 5 is a vertical sectional view of a part of the lower end of the can showing the bottom and reinforcing members about to be assembled.

Fig. 6 is a sectional view on line 6—6, 40 Fig. 1.

Fig. 7 is a layout of the sheet which forms two sides of the body of the can.

Fig. 8 is a perspective view of a lower 45 corner of the can viewed from the inside.

45 In the form of the invention disclosed in the drawings, the can consists of a rectangular body portion 11, a top reinforcing ring 12, a bottom 13 and bottom reinforcing members 14 and 15.

50 The body of the can is formed from two sheets of metal cut and punched as shown in Fig. 7.

The top reinforcing ring 12 is formed from a piece of band iron, bent into rectan-

gular shape with the ends welded together, 55 forming a continuous band.

The bottom 13 is formed from a rectangular sheet of metal flanged on four sides to form a downwardly extending flange with continuous corners, as shown in Fig. 6. 60

The reinforcing members 14 and 15 are formed from strips of sheet metal with the ends 23 bent up U-shaped, so that when the ends 23 are butted together, they form a rectangle, the corners of which are continuous, the ends 23 meeting at the center of the short sides as shown in Fig. 6.

The can is assembled by bending the lower ends 30 of each sheet 16 back upon itself forming a U-shaped channel 31, as shown in 70 Fig. 5. Each sheet is then bent at right angles on the dotted lines A—A and B—B, Fig. 7, the bend on the line A—A forming two sides of the body portion 11 and the bend on the line B—B forming a riveting 75 flange 32. After the sheets have been formed, as above described, the punched ends 34 of the wide side 35 of each sheet 16 is placed under the riveting flange 32 formed on the narrow side 36 of another similarly 80 formed sheet 16 and riveted together by means of rivets 37. The rivets are drawn and set up in one operation insuring a flush interior of the can free from all projecting rivet heads, as shown in section in Fig. 3. 85

The shell 11 with the U-shaped channel 31 on the inside of its lower end is now ready to receive the bottom 13 and reinforcing rings 14 and 15. The bottom 13 with its flange 40 extending downwardly, is inserted 90 from the top of the body 11 and pressed into place to a point close to the channel 31, the reinforcing strips 14 and 15 are now inserted between the inner wall of the flange 40 and the channel 31. This having been done, 95 the bottom continues on its downward movement until the lower side of the bottom 13 comes to rest on the top edge 42 of the inner wall 43 of the channel 31. Punching, riveting by means of rivets 45, and treating with a hot bath of solder completes the lower edge of the can.

The top reinforcing ring 12 is placed in position on the can by passing the ring 12 around the lower end of the can and forcing 100 the same upwardly until the upper edge of the ring 12 is flush with the upper edge of the can 11. The ring 12 is then riveted to

the can by means of rivets 47, the rivet holes in the ring 12 being countersunk for the purpose of drawing the rivet head flush with the inside of the can, as shown in Fig. 2.

- 5 It will be evident that the cutting of the corners at 44 of the sheets 16 facilitates the forming and assembling of the can at a sacrifice of some strength at the corners of the sheets 16. This, I overcome by forming the bottom with a continuous flange and by the use of the reinforcing strips 14 and 15 having continuous corners. When the outer sheet 16, flange 42, reinforcing strip 14 and 15 and inner wall 43 of the 10 channel are riveted together and treated with a hot bath of solder, the bottom rim of the can becomes substantially an integral structure and will withstand the hard usage to which cans of this type are subjected.
- 15 20 While I have shown and described my invention applied to a rectangularly shaped ice can, I do not wish to be understood as limiting myself to this type of can as the same may be applied to cans of various 25 shapes without departing from the spirit of my invention.

I claim as my invention:

1. An ice can comprising a body portion; a reinforcing ring at the top; cut corners 30 at the bottom of said body portion; channels

formed by making a single bend inwardly and upwardly of the side plates between the cut corners; a bottom; a continuous flange of a single thickness on said bottom extending into said channels; reinforcing members having continuous corners in said channels between the flange of the bottom and the inside wall of the channel, the channel portion of the side plates, flange and reinforcing members being riveted together 40 and treated with hot solder on the inside of the can along the joint between the sides of the can.

2. An ice can comprising a body portion cut at its lower corners; channels formed on 45 the lower edge of the body portion between the cut corners by making a single bend of the metal inwardly and upwardly, a bottom; a continuous flange formed on the bottom 50 extending into said channels by a single bend of the bottom at right angles thereto; reinforcing strips of flat metal between the flange of the bottom and the inner wall of the channel and means for securing said flange and reinforcing members in said 55 channel.

In testimony whereof, I have hereunto set my hand at San Francisco, California, this 19th day of April, 1921.

HOWARD G. TALLERDAY.
